(74) **Attorney, Agent, or Firm**—Birch, Stewart, Kolasch & Birch, LLP.

(57) **CLAIM**

The ornamental design for a catheter package, as shown and described.

DESCRIPTION

FIG. 1 is a perspective view of a catheter package showing our new design;

FIG. 2 is front elevational view thereof;

FIG. 3 is left side elevational view thereof;

FIG. 4 is a bottom plan view thereof;

FIG. 5 is a top plan view thereof;

FIG. 6 is a rear elevational view thereof;

FIG. 7 is a right side elevational view thereof;

FIG. 8 is a perspective view of a catheter package showing our new design;

FIG. 9 is front elevational view thereof;

FIG. 10 is left side elevational view thereof;

FIG. 11 is a bottom plan view thereof;

FIG. 12 is a top plan view thereof;

FIG. 13 is a rear elevational view thereof; and,

FIG. 14 is a right side elevational view thereof.

The parts shown with broken lines are not considered to be a part of the claimed design.
